UNITED STATES PATENT OFFICE.

ROSCOE BRATTON, OF LEBANON, INDIANA.

CHANGE-QUICK UNDERWEAR.

Application filed February 5, 1923. Serial No 616,975.

To all whom it may concern:

Be it known that I, Roscoe BRATTON, a citizen of the United States, residing at Lebanon, in the county of Boone and State 5 of Indiana, have invented certain new and useful Improvements in Change-Quick Underwear, of which the following is a specification.

This invention relates to under garments 10 such as are commonly spoken of as athletic underwear and has for its object the provision of such a garment which may be easily and quickly put on or removed even without the necessity of removing the outer 15 clothing and which shall be of improved construction and comfortable and efficient in use.

The invention is exemplified in the combination and arrangement of parts shown 20 in the accompanying drawing and described in the following specification, and it is more particularly pointed out in the appended claim.

In the drawing—
25 Fig. 1 shows the garment unfastened and opened; and

Fig. 2 is a pictorial illustration showing the garment in place on the wearer.

In Fig. 1, the numeral 10 designates the 30 main body of the garment which may be made from a single sheet of suitable fabric, the general shape of which is rectangular, as shown. The top portion of the garment is shaped to provide front and rear shoulder straps 11 and 12, respectively, having openings 13 between the straps for accommodating the arms. Suitable fastening means is provided at the ends of the straps which may consist of buttons and button holes, 35 snap fasteners, hooks and eyes, or any other suitable fastening device. The rear straps are somewhat longer than the front straps so that when the garment is in place the fastening will be located in front of the 40 shoulders in a convenient position, as shown in Fig. 2.

A slit 15 is provided at the central lower portion of the garment and triangular flaps 45 16 are secured to the edges of the slit portion by means of seams 17. The lower outer corners of the portion 10 may be cut away at an angle as shown at 18 so that when the garment is in place and the flaps 16 folded over the front portions of the lower limbs,

the edges of the flaps will overlap the edges 55 18 so that the edges may be secured together by fasteners 19 to form the legs of the garment. Fasteners 20 are provided to secure the garment along the front.

It will be apparent that any suitable 60 material may be used and the garment may be cut from woven cloth or may be formed by weaving, knitting or other suitable process in a single piece, or fashioned in any suitable manner.

It will be apparent that the garment may be put on or taken off in the usual manner by simply unbuttoning the fasteners 20, but it also may be put on or taken off by loosening all of the fastenings, in which case it 70 is unnecessary to move the arms or legs through any holes or openings so that the garment may be removed by simply drawing it away from the body without the necessity of removing any clothing from the legs or 75 arms. The convenience of this will be readily understood, as for instance, in cases where the under clothes have become wet with perspiration or soiled in any way the garment may be removed by separating the 80 shirt and trousers at the waist line, unfastening the securing devices, and drawing the garment away from the body at the waist line. The shirt, trousers, shoes, coat, vest and hat may all be retained in place, 85 if desired, during the removal or replacement of the garment.

In placing the fresh garment in position it is only necessary to place the straps 12 over the shoulders from the back beneath the 90 outer clothing and secure them to the front straps by the fasteners 14. The securing devices 19 and 20 may then be fastened and the outer garments readjusted.

Another advantage of the construction is 95 that it may be opened flat, as shown in Fig. 1, for laundering purposes. It is well known that it is much easier to iron a garment that opens into a flat position than one having tubular leg and arm portions, 100 whether the ironing is done by hand or by a mangle.

Various modifications may be made without departing from the spirit and scope of the invention as defined in the claim.

I claim:—

An under garment comprising a polygonal sheet having a central slit extending in-

wardly from the lower edge thereof to provide leg portions, the outer corners of said lower edge being angularly cut away, and separate triangular portions secured to the edges of said slit to fold about the legs of the wearer and to bring the free edges of said triangular portions into registration re-

spectively with the cut-away portions at the corners of said sheet along lines at the front and outer sides of the legs of the wearer.

In testimony whereof I have signed my name to this specification on this 26 day of January, A. D. 1923.

ROSCOE BRATTON
